UNITED STATES PATENT OFFICE.

MAURICE BLUMENTHAL, OF BROOKLYN, NEW YORK.

COMBINATION CONTAINER.

Application filed January 27, 1920. Serial No. 354,387.

To all whom it may concern:

Be it known that I, MAURICE BLUMENTHAL, residing at Brooklyn, in the county of Kings and State of New York, have invented certain new and useful Improvements in Combination Containers, of which the following is a specification.

This invention relates to a combination container, that is, a container which may be conveniently and easily used for containing and holding separate two or more different kinds of materials.

An object of the invention is to provide such a container which is simple of structure and attractive in appearance and from which the contents may be drawn or emptied selectively.

A further object is to provide a container which altho applicable in principle to use in numerous capacities is yet particularly adapted to be embodied for containing two or more different kinds of powders, such as are ordinarily in use as toilet accessories, for instance, tooth powder, shaving powder and talcum powder. A container of this character is particularly adapted for use by travellers, and the like, in that it combines in a single container what has heretofore required two or more separate containers.

A further object is to provide means whereby the contents of the different compartments of the container may be seen at least sufficiently for determining the quantity of material in each compartment.

A further object is to provide a common closure member for the several compartments by which the contents of the compartments may be selectively emptied.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown merely a preferred form of embodiment of the invention:

Figure 1 is a side elevational view of a container constructed in accordance with

this invention, a portion of the container being broken away for better illustrating the structural form of the container.

Figure 2 is a top plan view of the closure device.

Figure 3 is a transverse sectional view thru the container, and

Figure 4 is a side elevational view of a complete container illustrating a slightly modified form.

Figure 5, shows a modification.

Referring to the drawings for describing in detail the structure which is illustrated therein, the reference character L indicates the main body, or casing, of the container. As shown in Fig. 3, this is preferably elliptical in cross section, altho it may, of course, be of any other desired contour. The lower end of the container is closed by a bottom piece G, while the upper end of the container has fitted thereto a cover piece H upon which is a rotatably mounted closure member 1.

The interior of the container may be divided into any desired number of compartments, as 2, 3 and 4, by means of suitable partition walls 5.

The closure member 1 has a single opening 6 therein which is adapted upon rotation of the closure member to mate with any selected set of openings 7, 8 and 9, the openings 7, 8 and 9 being formed thru a stationary closure member 10 and being arranged so that they communicate with the compartments 2, 3 and 4 respectively.

When it is desired to pour out, or remove, any of the contents of one of the compartments, the closure member 1 is rotated to uncover the set of openings in the closure member 10 communicating with that particular compartment. The closure member 11 is shaped so that the main portion of its top wall 11 at this time overlies and closes each of the other sets of openings so that the contents of only one of the compartments can be removed at a time.

The sets of openings 7, 8 and 9 of the closure member 10 are so disposed with relation to the opening 6 in the closure member 1 that when desired the closure member 1 may be rotated to cause the opening 6 thereof to overlie a non-apertured portion 12 of the closure member 10, thus at such time closing all of the compartments.

Any appropriate means may be embodied

2
in the device for indicating the appropriate positions for the closure member 1 in order to enable the operator to empty the contents of any particular compartment. For instance, the container may be embossed or otherwise furnished with indications, such as the words "Tooth powder," "Shaving powder" and "Talcum powder," such indications, or words, being placed in such radial position as to be nearest to the set of openings 7, 8 or 9 which should be uncovered for producing the desired result.

In order that the contents of the separate compartments may be conveniently inspected so that the owner of one of the containers may know particularly the quantity of contents still within the compartments, suitable windows 13 may be provided. These windows may preferably have a horizontal portion 14 and a vertical portion 15, the portion 15 providing a view of the top level of the contents when there is still a considerable quantity within the compartment, and the portion 14 extending across the lower end of the portion 15 and adjacent to the bottom of the compartment serving to indicate particularly when the level of the contents has become very low. The portion 14 will thus at once serve as a prominent indication when the level of the contents is very low, and as a broad window thru which practically the entire contents may be readily inspected. The windows as thus constructed provide all requisites enabling them to well serve their intended purposes, and yet they contain no large expanse of material which would be likely to be broken or injured during the handling of the container.

40 A container embodying the general features as above set forth may be readily carried in a travellers grip and will provide means for quickly and easily using any one or all of the different articles contained and 45 it will at the same time occupy no more room within the grip than has been heretofore occupied by an ordinary talcum powder can.

The same principles, of course, can be applied to containers for any other different commodities, either powders, liquids, or otherwise, and the same degree of efficiency and simplicity be attained.

The partitions 5, may, of course, be arranged so as to determine the relative sizes of the different compartments, it being anticipated that a relatively larger compartment may be provided for containing the particular material which is the most used, 55 and a relatively smaller compartment for the material which is the least used.

In the drawing the container illustrated is similar in general exterior appearance to an ordinary talcum powder can, the closure

member 1 being centrally disposed of the cover piece H, and the cover piece H flaring out to embrace the upper edges of the main body portion L. In this instance the partitions 5 are inclined, being furthest spaced apart at their lower ends, and having their upper ends extending into the closure member 1. The partitions 5 could be readily positioned for making the different compartments of any proportionate sizes 75 76 77 78 79 80 81 82 83 84 85 86 87 88 89 90 91 92 93 94 95 96 97 98 99 100 101 102 103
